(57)

CLAIM

The ornamental design for a speedloader holder, as shown and described.

DESCRIPTION

FIG. 1 is a perspective view of the speedloader holder. The broken lines show a speedloader that forms no part of the claimed design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The material shown in broken lines is environment and forms no part of the claimed design.

1 Claim, 4 Drawing Sheets
